UNITED STATES PATENT OFFICE.

WILLIAM E. SHANKLIN, OF SPRINGFIELD, ILLINOIS, ASSIGNOR TO SHANKLIN MANUFACTURING CO., OF SPRINGFIELD, ILLINOIS, A COPARTNERSHIP.

DESIGN FOR A LAMP BODY.

Application filed December 2, 1921. Serial No. 519,523. Term of patent 14 years.

To all whom it may concern:

Be it known that I, WILLIAM E. SHANKLIN, a citizen of the United States, residing at Springfield, in the county of Sangamon and State of Illinois, have invented a new, original, and ornamental Design for a Lamp Body Adapted for Use on Carbide Lamps or the like, of which the following is a specification, reference being had to the accom-

panying drawing, forming a part thereof.

Fig. 1 is a top plan view of the body; Fig. 2 is a side elevation of the same; and Fig. 3 is a bottom plan view.

I claim:

The ornamental design for a lamp body, as shown.

WILLIAM E. SHANKLIN.
